(57) **CLAIM**

I claim the ornamental design for a medical tag cover with a USB drive pocket, as shown and described.

DESCRIPTION

FIG. 1 is a front perspective view of a medical tag cover with a USB drive pocket, shown with environment for ease of disclosure;

FIG. 2 is a rear perspective view thereof, shown with environment for ease of disclosure;

FIG. 3 is a rear elevational view thereof;

FIG. 4 is a front elevational view thereof;

FIG. 5 is a right-side elevational view thereof;

FIG. 6 is a left-side elevational view thereof;

FIG. 7 is a top plan view thereof; and,

FIG. 8 is a bottom plan view thereof.

The broken lines showing a medical tag and a key chain ring in FIGS. 1 and 2 depict environmental matter and form no part of the claimed design. The broken lines in FIG. 7 depict portions of the medical tag and a key chain ring that form no part of the claimed design.

1 Claim, 5 Drawing Sheets
